ELECTRIC RESISTANCE

Eugène Gindre, Gennevilliers, France, assignor to
 Société Anonyme De Carbone, Gennevilliers,
 France

Application October 23, 1931, Serial No. 570,565
 In France March 26, 1931

4 Claims. (Cl. 201—51)

As is well known, electric resistances have been made by means of a pile of carbon discs or washers, and the resistance has been varied by modifying the mechanical pressure exerted on this

pile. To a small pressure corresponds a high resistance and, when the pressure increases, the resistance diminishes.

It will easily be understood why by increasing the pressure, the resistance is diminished.

10 The discs or washers placed one on the other are only in contact at a small number of points. The electric resistance is therefore very high when there is no pressure. But, if a pressure is exerted, the discs or washers are distorted owing 15 to their resiliency; the surface area in contact is considerably increased and the resistance proportionally diminishes.

15 In the various applications of resistances of this type, it is usually desired that the increase 20 of resistance should be very rapid. For obtaining this, it has been suggested to make very thin and consequently very resilient washers which are very easily distortable, but these washers are very fragile and break very easily.

25 Now, the heat due to the passage of the current is dissipated only by the side surface of the discs or washers. It results that a thin disc or washer is costly relatively to the amount of heat it is capable of dissipating. This is another 30 inconvenience of thin discs or washers in addition to their fragility.

The present invention has for its object to provide a device in which the electric resistance may be rapidly varied without having to use thin 35 discs or washers.

According to the invention each resistance element consists of a block having surfaces of two different contours, so that when two blocks are fitted together and no pressure is exerted, the 40 two adjacent blocks are in contact only at their periphery and there is between them a space increasing towards the centre of the block. Owing to this arrangement, the blocks, although thick, can be resiliently distorted, without breaking, and 45 produce a rapid variation of the ohmic resistance.

In order that the invention may be clearly understood, the accompanying drawing illustrates a form of construction, in the particular case in 50 which the blocks have conical surfaces.

Fig. 1 is an elevation of a resistance block.

Fig. 2 is a corresponding plan view.

Fig. 3 shows a pile of blocks fitted in each other.

55 As illustrated in the drawing, each block *a*, in-

stead of being bounded by two plane surfaces, has two conical surfaces *b* and *c*, the angle at the apex of *b* being greater than that at the apex of *c*.

It results therefrom, that, when two blocks are 60 fitted into each other, Fig. 3, they are in contact only at their periphery. A pile of blocks presents a high electric resistance, but when an end-wise pressure is exerted on this pile, each of these blocks is distorted owing to its resiliency and the 65 zones of contact increase until the surfaces *b* and *c* are entirely in contact.

Instead of conical surfaces, the faces of the blocks can be of different shape. They can constitute for instance pyramids, or generally speaking, any surface such that, without pressure, there is contact only at the periphery and there is between adjacent blocks a space increasing in height towards the centres of the blocks.

The contour of the block can be of any shape, 75 round, square, oval or the like.

The new device presents important advantages.

Firstly, the blocks are easily assembled owing to their shape. The entire structure has naturally a great stability. The blocks need not even 80 be guided. However, it is desirable to hold the column either by means of side guides, or by placing it in a tube, or by threading the blocks, perforated at their centre, on a spindle, etc.

Another characteristic advantage of the invention 85 consists in the rapid diminution of the electric resistance with the pressure, and reversely.

Moreover, the variation of resistance is continuous; the new resistances avoid the well known disadvantages of rheostats provided with contact 90 pieces, in which the interval between two contact pieces is relatively large.

Moreover in such rheostats the contact pieces are subject to rapid wear whereas the new device does not require any maintenance, as it is not 95 subjected to any wear.

The resistance blocks constituted as just stated are very strong and do not break under the action of the pressures to which they are subjected.

The new resistances are capable of receiving 100 numerous applications, for instance for the small motors of sewing machines, for the dynamos used for lighting railway trains, for adjusting the voltage of generators, for the dynamos of motor cars. They are as useful for large as for small machines 105 and can be used as energizing rheostats, etc.

The above arrangements are given by way of example only; the details of construction, forms, dimensions and materials used may be varied according to circumstance without departing 110

thereby from the scope of the invention.

I claim:

1. A carbon pile resistance adapted to be subjected to pressure, comprising a series of superposed carbon disks wherein each disk has a concave surface upon one side and a convex surface upon the other side, and arranged so that the concave surface of each disk directly faces the adjacent convex surface of the next disk in the series and the disks make mutual contact solely at the peripheries thereof.

10 15 20

2. A carbon pile resistance adapted to be subjected to pressure, comprising a nested series of superposed carbon disks wherein each disk has a conical concave surface upon one side and a conical convex surface upon the other side, and arranged so that the conical concave surface of each disk directly faces the adjacent conical convex surface of the next disk in the series and the disks make mutual contact solely at the peripheries thereof.

3. A carbon pile resistance adapted to be sub-

jected to pressure, comprising a nested series of superposed carbon disks wherein each disk has a conical concave surface of a predetermined inclination upon one side and a conical convex surface of a different inclination upon the other side, and arranged so that the conical concave surface of each disk directly faces the adjacent conical convex surface of the next disk in the series and the disks make mutual contact solely at the peripheries thereof.

80 85 90 95

4. A carbon pile resistance adapted to be subjected to pressure, comprising a nested series of superposed carbon disks wherein each disk has a conical concave surface forming a relatively smaller apex angle upon one side and a conical convex surface forming a relatively greater apex angle upon the other side, and arranged so that the conical concave surface of each disk directly faces the adjacent conical convex surface of the next disk in the series and the disks make mutual contact solely at the peripheries thereof.
